TYPE-WRITING MACHINE.

No. 869,037.

Specification of Letters Patent.

Patented Oct. 22, 1907.

Application filed September 30, 1905. Serial No. 280,740.

To all whom it may concern:

Be it known that I, OSCAR WOODWARD, a citizen of the United States, and a resident of the borough of Manhattan, city of New York, in the county of New York and State of New York, have invented certain new and useful Improvements in Type-Writing Machines, of which the following is a specification.

My invention relates to typewriting machines, and it has for its principal object to provide an improved means for imparting a step-by-step motion to the carriage in a direction the reverse of that normally imparted to said carriage by the escapement mechanism.

My invention consists in certain features of construction and combinations and arrangements of parts, all of which will be fully set forth herein and particularly pointed out in the claims.

My invention is illustrated in the accompanying drawings in which.

Figure 1 is a front to rear vertical sectional view of so much of a typewriting machine as is necessary to illustrate my invention. Fig. 2 is a fragmentary rear elevation of the same with parts omitted and broken away. Fig. 3 is an enlarged detail view of the escapement wheel shaft and its connected parts in vertical section. Fig. 4 is a sectional view of the same on the line *x* *x* of Fig. 3 and looking in the direction of the arrow at said line. Fig. 5 is an enlarged detail isometric view of the back spacing pawl and guide member. Fig. 6 is a detail view in rear elevation showing the back spacing pawl and guide member in operated position and the cooperating ratchet wheel. Fig. 7 is a detail plan view of the sheet metal blank from which the back spacing pawl is formed.

My invention may be readily adapted to various forms of typewriting machines. The main frame of the machine shown in the drawings comprises a base portion having side plates 1 connected together at the rear by a transverse rear plate 2 and by a back shelf 3. Posts 4, rising from said base portion support a top plate 5 from which rise posts or brackets 6 that support rails 7 having in their upper sides grooved ball races in which play antifriction bats or rollers 8 that coöperate with grooved rails forming parts of a carriage 9 in which is mounted a platen 10. The carriage 9 may be drawn across the machine by the usual spring drum (not shown) and its motion may be controlled by mechanism comprising a feed rack 11 mounted on the rear ends of arms 12, the forward ends of which are pivoted at 13 to the carriage 9. Said feed rack is normally held in the position shown in Fig. 1 by a spring or springs 14 which are secured to the carriage 9 by screws 15 and which at their free ends engage the arms 12; the said feed rack may be lifted to release the carriage from its feed devices by any suitable means. The feed rack 11 is toothed on its lower side to coöperate with a feed pinion 16 which

is mounted on the forward end of a shaft 17 which is journaled in a housing or bracket 18 secured to the top plate 5.

At its rear end the shaft 17 has loosely mounted thereon an escapement wheel 19 which is controlled by suitable feed dogs (not shown) which, in turn, are controlled by the character keys and space key of the machine in a manner well known in the art. A small ratchet wheel 20 is formed on or secured to the front face of the escapement wheel 19 and said ratchet wheel 65 is engaged by a pawl or pawls 21 pivoted on pins 22 projecting from the web of a circular housing or wheel 23 which is mounted on the shaft 17 and rigidly secured in place on said shaft, in front of the escapement wheel 19 and ratchet wheel 20, by means of a key 24 inserted 70 in a groove in the shaft 17 and a corresponding groove in the hub of the wheel or housing 23. Said hub is elongated toward the front of the machine, the housing 23 being bored out to receive it. The wheel or housing 23 is formed with an annular rim, as shown, which extends toward the back of the machine approximately to the escapement wheel 19, so that the web and rim of said wheel 23 inclose the ratchet wheel 20 and the pawls 21 so as to form a housing therefor in a manner well known in the art. Each of the pawls 21 is engaged by the free end of a spring 25, the other end of which is secured to the inner face of the rim of the wheel 23. The escapement wheel 19 is prevented from moving along the shaft 17 toward the back of the machine by a collar 26 mounted on said shaft back of 80 said escapement wheel and secured in position on said shaft by a set screw 27. The construction is such that when the escapement wheel 19 is held by the feed dogs, the pawls 21 prevent rotation of the wheel 23, the shaft 17 and the pinion 16 in the direction in which the spring drum, acting through the feed rack 11, tends to turn these parts; but when a return motion is imparted to the carriage by any means, the pawls 21 snap over the teeth of the ratchet wheel 20.

My back spacing mechanism comprises a ratchet wheel rigidly mounted on the shaft 17 and a pawl adapted to turn said ratchet wheel clockwise, looking from the front. I prefer to utilize the drum or housing 23 as the ratchet wheel and to this end notches 28 are cut in the periphery of said drum, the number of said 90 notches being equal to the number of teeth in the escapement wheel 19.

The back spacing of the carriage is effected by a back spacing key 29 at the keyboard of the machine and mounted on the forward end of a key lever 30, 105 the notched rear end of which is pivoted on a pivot plate 31 which extends across the back end of the machine. The pivot plate 31 has the form of an angled bar, one side or flange of which extends downward from the shelf 3. Said downwardly extending flange 110

has a series of slots 33 (Fig. 2) formed in its lower edge and the key lever 30 and the key lever of the character keys of the machine stand in these slots in the manner indicated in Figs. 1 and 2.

5 The key lever 30 is provided with a returning spring 34, the lower end of which is connected to said key lever and the upper end of which is connected with a hook or bracket 35 secured to the back shelf 3. The forward end of the key lever 30 plays in a slot in a comb' plate 36 10 which guides its motion. The key lever 30 is connected by a two-part adjustable link 37 with an arm 38 projecting toward the front of the machine from a transverse rock shaft 39 that is journaled in brackets 40 depending from the top plate 5. The arm 38 has 15 a hub that is secured to the shaft 39 by set screws 41. At a point approximately beneath the feed pinion 16 the shaft 39 has projecting therefrom toward the rear of the machine an arm 42, the hub of which is secured on said shaft by a set screw 43. Endwise motion of the 20 shaft 39 is prevented by the engagement of the hubs of the arms 38 and 42 with the brackets 40.

The free end of the arm 42 has pivoted thereto a pawl 1 and guide member 44, the stem of which extends upward through an opening in the top plate 5 25 and the operative parts of which engage the ratchet wheel 23. Said member 44 has the form best shown in Fig. 5. At its lower end said member has projecting therefrom through a hole in the arm 42, a shouldered rivet 45, against the end of which a spring 46 30 bears, forming a readily-detachable clip. Said member has a portion thereof formed into a pawl 47 that is adapted to engage the notches in the wheel 23 to turn said wheel for back spacing the carriage. Said member is also formed with a curved guide arm 48 of inverted U-shape which lies in front of the wheel 23 and extends over the housing 18 and down on the right-hand side of said housing. The member 44 is preferably made of sheet metal by bending up a blank of the form shown in Fig. 7. Said blank is bent along the 35 line a of said Fig. 7, so that the flat side of the pawl 47 engages the periphery of the wheel 23 and the flat face of the curved arm 48 is in position to engage the front face of said wheel 23 and thus prevent motion of the member 44 toward the back of the machine.

45 The machine shown in the drawings has a rod 49 that is mounted in brackets 50 that rise from the top plate 5. Said rod passes underneath the housing 18 a little in front of the wheel 23 and I utilize said rod to prevent the pawl from falling toward the front of the machine. 50 To this end the curved arm 48 is formed with a tail portion 51 that stands behind the rod 49 when the pawl is operated and prevents motion of said pawl toward the front of the machine. The curved guide arm 48 is so formed and the parts are so proportioned that when 55 the arm 42 is in its normal or lower position, the pawl 47 is out of engagement with the wheel 23 but stands just beneath one of the notches 28 in said wheel, the pawl being held in this position by the engagement of the curved guide arm 48 with the housing 18. When 60 the key 29 is depressed, the arm 42 is elevated and the pawl 47 is moved into the notch 28 and operates the wheel 23, turning it clockwise from the front, a distance of one notch or far enough to cause each of the pawls 21 to drop behind the next succeeding tooth in the ratchet 65 wheel 20 which is rigid with the escapement wheel 19.

This movement of the parts effects a back spacing movement of the carriage a letter space distance and a back space of the carriage for a letter space distance is effected at each depression of the key 29. It will be understood that in the machine here shown said escapement wheel is held against backward rotation by the usual feed dogs, and that in machines in which the feed dogs are adapted to permit backward rotation of the escapement wheel, said escapement wheel may be rigidly mounted on the shaft 17, and the ratchet 20 and pawls 21 may be dispensed with, if desired, so far as certain features of my invention are concerned. As the member 44 rises upon the depression of the key 29 it is guided in its motion by the engagement of the pawl 47 with the wheel 23 on the one hand and by the engagement of the curved guide arm 48 with the housing 18 on the other, so that said pawl is free to follow the motion of the wheel but cannot come out of engagement with said wheel. The lower part of the right-hand side of the guide arm 48 is formed with a curve 52 somewhat sharper than the other parts of the curve of said arm and at the moment when the pawl 47 reaches the highest point in its stroke this sharper curve 52 engages the right-hand side of the housing 18 below the vertical center of said housing and arrests the motion of the pawl. At 90 the same time, the member 44 is jammed, the curve 52 tending to pull the pawl 47 forcibly into the notch 28 in the wheel 23 with the result that said wheel is positively arrested in its motion and any overthrow of the wheel and of the carriage beyond the single letter space 95 distance is thus positively prevented. When the key 29 is released the member 44 drops downward, such downward motion moving the curved portion 52 of the arm 48 out of engagement with the housing 18 and permitting the pawl 47 to slip out of the notch 28 and to 100 return to normal position beneath the next succeeding notch 28.

The shaft 39 is provided with a returning spring 53 (Fig. 2). One end of said shaft projects through and beyond one of the brackets 40 and the spring 53 is coiled about this projecting end of the shaft. One end of said spring is inserted in a hole in the bracket 40 and the other end is secured in the same or in any suitable manner to a collar 54 which surrounds said shaft and which is formed on its outer end with a slot 55 for the insertion of a tool similar to a screwdriver. The collar 54 is adapted to be secured in position on the shaft 39 by a set screw 56. The tension of the spring 53 may be regulated by loosening the set screw 56 and turning the collar 54 by means of the tool referred to until the desired tension of the spring 53 has been produced, and then again tightening the screw 56.

It will be perceived that whenever it is desired to back step the carriage, the key 29 may be depressed until it is arrested by the jamming of the curved portion 52 of the arm 48 engaging the housing 18 with the result that the wheel 23, shaft 17 and pinion 16 will be turned toward the right a suitable distance to step the carriage back one letter space distance. This operation may obviously be repeated as often as desired and the key 120 may be struck sharply and quickly as the means described positively prevent any overthrow of the parts. It will also be perceived that as the pawl 47 is normally out of engagement with the wheel 23, the carriage may be moved freely in either direction without it being 125

interfered with by the back spacing mechanism. It will also be perceived that the rock shaft 39, being mounted in the lugs or brackets 40 depending from the top plate, is the only part of the back spacing mechanism that is secured to the framework of the machine above the base portion of said framework and that this is secured in such a position that it is itself readily detachable without interfering with other parts of the mechanism and its position is such that it does not interfere with the assembling of the other parts of the mechanism nor their removal in case of need.

Various changes may be made in the details of construction and arrangement without departing from my invention.

15 The means shown in the present case whereby the key lever 30 is fulcrumed at its rear end, are claimed in my pending application filed August 15th, 1905, Serial No. 274,288.

What I claim as new and desire to secure by Letters 20 Patent, is:

1. In a typewriting machine, the combination of a carriage; a shaft geared to said carriage; a ratchet wheel on said shaft; a back spacing pawl adapted to operate said ratchet wheel but normally out of engagement therewith; a key for operating said pawl; and means for preventing overthrow of said ratchet wheel when said pawl is operated. 55
2. In a typewriting machine, the combination of a carriage; a back spacing ratchet wheel geared to said carriage; a back spacing pawl for operating said ratchet wheel, said pawl having a curved arm for engaging a part of the machine to guide the motion of said pawl and to jam said pawl against the ratchet wheel at the end of the stroke to prevent overthrow of said ratchet wheel; and a key for operating said pawl. 60
3. In a typewriting machine, the combination of a carriage; a shaft geared to said carriage; a housing in which said shaft is journaled; a back spacing ratchet wheel on said shaft; a back spacing pawl for operating said ratchet wheel; a guide arm connected with said pawl and co-operating with said housing to guide said pawl out of engagement with said ratchet wheel when the pawl returns to normal position; and a key for operating said pawl. 65
4. In a typewriting machine, the combination of a carriage; a back spacing ratchet wheel geared to said carriage; a back spacing pawl for operating said ratchet wheel; a guide member connected with said pawl and adapted to guide said pawl out of engagement with said ratchet wheel when said pawl returns to normal position and to forcibly engage said pawl with said ratchet wheel at the end of the positive stroke of said pawl; and a key for operating said pawl. 70
5. In a typewriting machine, the combination of a carriage; a feed rack on said carriage; a feed shaft geared to said feed rack; a housing in which said feed shaft is journaled; an escapement wheel mounted on said feed shaft; a ratchet wheel rigidly mounted on said feed shaft in front of said escapement wheel and having pawl and ratchet connection with said escapement wheel; a back spacing pawl adapted to operate said ratchet wheel; and a guide arm on said back spacing pawl adapted to engage said housing to guide the motion of said pawl. 75
6. In a typewriting machine, a back spacing pawl formed of sheet metal and having a curved guide arm integral with said pawl and bent off therefrom in such fashion that the flat face of said guide arm is substantially at right angles to the flat face of said pawl. 80
7. In a typewriting machine, the combination of a carriage, a shaft geared to said carriage; a back spacing ratchet wheel mounted on said shaft; a back spacing pawl for operating said ratchet wheel, said pawl having a U-shaped guide arm, the inside curve of which is adapted to engage a part of the machine and guide the motion of said pawl; and a key for operating said pawl. 85
8. In a typewriting machine, the combination of a carriage; a shaft geared to said carriage; a housing in which said shaft is journaled; a back spacing ratchet wheel mounted on said shaft; a back spacing pawl adapted to engage said ratchet wheel on one side of said housing and having a guide arm adapted to engage the other side of said housing to guide the motion of the pawl; and a key for operating said pawl. 90
9. In a typewriting machine; the combination of a carriage; a shaft geared to said carriage; a ratchet wheel mounted on said shaft; a housing in which said shaft is journaled; a pawl adapted to engage said ratchet wheel at one side of said housing and having a guide arm extending to the other side of said housing, said guide arm having a part adapted to engage said housing at the end of the stroke of the pawl and to cause said pawl to be forcibly pressed against said ratchet wheel to prevent overthrow; and a key for operating said pawl. 95
10. In a typewriting machine, the combination of a carriage; a feed rack therefor; a feed pinion engaged by said feed rack; an escapement wheel; pawl and ratchet mechanism for operatively connecting said escapement wheel and feed pinion; a circular housing for inclosing said pawl and ratchet mechanism; grooves cut in the periphery of said circular housing to form a back spacing ratchet wheel thereof; a back spacing pawl co-operating with said ratchet wheel; and a key at the keyboard of the machine for actuating said back spacing pawl. 100

Signed at the borough of Manhattan, city of New York in the county of New York and State of New York this 28th day of September A. D. 1905.

OSCAR WOODWARD.
